UNITED STATES PATENT OFFICE.

HERMAN BELTZ AND ROBERT MOIR, OF MINNEAPOLIS, MINNESOTA.

ELEVATOR-DOOR HANGER.

1,148,652.

Specification of Letters Patent. Patented Aug. 3, 1915.

Application filed February 10, 1915. Serial No. 7,451.

To all whom it may concern:

Be it known that we, HERMAN BELTZ and ROBERT MOIR, citizens of the United States, residing at Minneapolis, in the county of 5 Hennepin and State of Minnesota, have invented certain new and useful Improvements in Elevator-Door Hangers; and we do hereby declare the following to be a full, clear, and exact description of the invention, 10 such as will enable others skilled in the art to which it appertains to make and use the same.

Our invention relates to door hangers for elevator shafts, and has for its main object 15 to provide extremely simple and highly efficient differential door actuating mechanism therefor.

Generally stated, the invention consists of the novel devices and combinations of devices hereinafter described and defined in 20 the claims.

In the accompanying drawings which illustrate the invention, like characters indicate like parts throughout the several views.

25 Referring to the drawings: Figure 1 is a view chiefly in side elevation but with some parts sectioned, showing our invention as applied to a two-section elevator door; Fig. 2 is a horizontal section taken approxi- 30 mately on the line $x^2 x^2$ on Fig. 1; Fig. 3 is a fragmentary view partly in side elevation and partly in vertical section of some of the parts shown in Fig. 1; Fig. 4 is a detail showing certain parts sectioned on the line 35 $x^4 x^4$ on Fig. 3; and Fig. 5 is a section showing certain parts sectioned on the line $x^5 x^5$ on Fig. 3.

The numerals 2 and 3 indicate the movable doors or door sections. In this im- 40 proved structure, we preferably provide a pair of parallel laterally spaced rails 4 for each door section, and these pairs of rails are parallel to each other and spaced apart laterally and are rigidly secured to and sup- 45 ported from an elongated rectangular hous- ing 5, which, in turn, is rigidly secured to the upper horizontal portion of the door frame.

Arranged to run on each track or pair of 50 rails 4 is a door supporting truck or traveler made up, as shown, of a pair of parallel metal bars 6, and truck wheels 7. The bars 6, between the wheels 7, are rigidly connected and spaced by spacing blocks 8. The 55 wheels 7, preferably, have projecting central flanges that run between the rails of the

coöperating track, and thus hold the rollers against lateral displacement from the track. Preferably, the rollers 7 are connected to the truck bars 6, by ball-bearing journals 9. 60

The trucks or travelers which independ- 65 ently support the several door sections, may be alike or substantially alike in this im- proved arrangement. The said door sec- tions are adjustably hung from the respec- 70 tive trucks or travelers, by hanger bolts 10 which are passed downward through verti- cal holes in the respective spacing blocks 8, depending between the rails of the corre- 75 sponding track, and at their lower ends, are threaded and screwed into the top bars of the respective door sections. Lock nuts 11 on the threaded ends of said hanger bolts press against the top bars of the door sec- 80 tions and thus lock the hanger bolts 10 against rotation and the door sections in the desired vertical adjustment. Just below 85 the lower edges of the coöperating rails 4, each hanger bolt is provided with anti-fric- tion ball bearing devices for engagement with the lower edges of the said rails. As shown, 90 such ball bearing devices comprise a washer- like ball runway 12, bearing balls 13, a ball spacing ring or cage 14 and the supporting nut 15, all of which are applied around the 95 respective hanger bolts. The balls in this arrangement, with the cage 14, are free to rotate, and some one or the other of the said balls are always engaged with the lower edge of one or the other of said rails, so as 100 to thereby prevent the door sections from being raised, either by direct vertical move- 105 ment or by angular lifting movements. By adjustments of the nuts 15, the ball bearing device or stops may be always set in proper relation to the lower edges of the coöperat- 110 ing rails. The said ball bearing device be- ing free to rotate, may move in the one di- rection or the other, depending on the di- rection of the travel of the door, and in which the pressure friction is applied. There will always be some slight inaccura- cies in the location of the rails 4 so that in practice, the balls of the rotary ball bearing stop devices, will not simultaneously en- gage the lower edge of both of the pair of coöperating rails, but will always engage with one or the other thereof, whenever the force is applied to the door tending to take the same up at one edge.

What we claim is:

1. A door hanger comprising a track, a

traveler movable on said track, hangers depending from said traveler to a point below said track, a door carried by said hangers below said track, an annular ball runway supported by said hanger below said track, and a series of bearing balls held to run on said runway and engageable with the lower edge of the said track.

2. A door hanger comprising laterally spaced parallel track rails, a truck movable on said track, hanger bolts carried by said truck and depending between said track rails, a door carried by the lower ends of said hanger bolts, a ball runway adjustably mounted on the lower ends of said hanger bolts, and an endless series of balls held for movement on said ball runway and engageable with the lower edges of the overlying rails.

3. A door hanger comprising laterally spaced track rails coöperating to form a track, a truck having wheels located, one ahead of the other, and arranged to run on both of said rails, hangers carried by said

truck and depending between said rails, a 25 door carried by the lower portions of said hangers, and an anti-friction device carried by said hangers and engageable with the lower edges of said rails.

4. A door hanger comprising laterally spaced track rails coöperating to form a track, a truck having wheels located, one ahead of the other and arranged to run on both of said rails, hangers carried by said truck and depending between said rails, a 30 door carried by the lower portions of said hangers, an anti-friction device carried by said hangers and engageable with the lower edges of said rails, and means for vertically adjusting said anti-friction devices 35 vertically in respect to said rails.

In testimony whereof we affix our signatures in presence of two witnesses.

HERMAN BELTZ.
ROBERT MOIR.
